CLAIM

We claim the ornamental design for a display screen or portion thereof with graphical user interface, as shown and described.

DESCRIPTION

This design patent application is a Continued Prosecution Application under 37 C.F.R. 1.53(d) of U.S. patent application Ser. No. 29/717,213, filed on Dec. 16, 2019.

FIG. 1 is a front view of a first embodiment of a display screen or portion thereof with graphical user interface showing our new design;

FIG. 2 is a front view of a second embodiment thereof; and, FIG. 3 is a front view of a third embodiment thereof.

The outermost broken line perimeter illustrates a display screen or portion thereof and forms no part of the claimed design. The remaining broken lines depict portions of the graphical user interface and form no part of the claimed design.
